United States Patent Office.

HENRY A. HORN, OF NEW YORK, N. Y.

Letters Patent No. 86,340, dated January 26, 1869.

IMPROVEMENT IN HOOP-SKIRTS.

The Schedule referred to in these Letters Patent and making part of the same.

To all whom it may concern:

Be it known that I, HENRY A. HORN, of the city, county, and State of New York, have invented certain new and useful Improvements in Skirts, of which the following is a full, clear, and exact description, reference being had to the accompanying drawing, making part of this specification, and in which—

Figure 1 represents a perspective view of my improved skirt.

Figure 2, a front elevation of the same.

My invention relates to that class of hoop-skirts which are caused to assume the "panier"-form when adjusted for wear; and consists in providing such a skirt with elastic retaining-bands, attached as will be more fully described, and providing it with a front, of a flexible fabric, the hoops of the skirt extending around but a portion of the skirt, and being entirely omitted at the front, for purposes hereinafter set forth.

To suit the prevailing fashion, hoop-skirts are made to fit very closely to the wearer, except at the bustle-point, where, by various attachments, they are made to protrude so far as to give the appearance of a panier-attachment.

To enable the wearer to freely use her limbs, I have found it desirable to omit the hoops at the front, where I provide a flexible band, or cloth, to which, at its either side, the wires or hoops of the skirt (extending around the body and forming the rest of the skirt) are attached.

This arrangement renders the skirt collapsible when under pressure in crowded places, and permits the skirt to hug the body closely at the front, without inconvenience to the wearer, this latter effect being necessary to distend the skirt behind, it being accomplished by means of elastic bands attached to the front ends of the hoops, and passing about the body.

It may be observed that inelastic tapes may be used, but an elastic attachment is found to be most advantageous.

I am aware that hoop-skirts have been distended in their rear portion, by means of tape or cord-attachments, but such skirts are objectionable, from the fact that the metallic wires are held in contact with the limbs of the wearer, causing much inconvenience in walking, and so much discomfort as to preclude their use.

To enable others skilled in the art, to make, construct, and use my invention, I will now proceed to describe it in detail.

In figs. 1 and 2, my improved skirt is represented as having its rear part, A, made of elastic wire, and other suitable material, in the usual manner of making skirts, shaped in the "panier" or other suitable form, as may be desired, but the hoops, or elastic wires, are made to extend only two-thirds or three-fourths round the circumference of the skirt, leaving in front an open space, free of "hoops" or elastic wire, as shown in the drawing.

The front part of the skirt consists of a number of parallel bands, or tapes, or cords, a, extending from the bottom nearly to the top of the skirt, and running crosswise, and firmly secured, in any desired manner, to the sides of the rear or "hoop" part of the skirt.

At or about one-fourth its length from the top of the skirt, is secured to the sides of the same a pair of elastic bands, B B, arranged and secured crosswise, as shown in the drawing, in such a manner as to pass around and rest on the buttocks of the wearer, with the view of keeping the "hoop"-part in the desired position—well back—so as to maintain and insure a graceful shape to the folds of the upper skirt, and to prevent the hoop-portion coming forward, which has been heretofore experienced as a great inconvenience in all hoop-skirts.

At or about one-eighth of its length from the top of the skirt is secured another elastic band, B', fastened to each side, preventing the usual flare on the sides and on the hips, as shown in the drawing.

What I claim as my invention, and desire to secure by Letters Patent, is—

As an article of manufacture, a hoop-skirt formed with the fabric or tape-portion a, and hooped portion A, and provided with elastic attachment, B B b, for adjusting it in position upon the wearer, substantially as shown and described.

HENRY A. HORN.
